UNITED STATES PATENT OFFICE

FREDERICK W. ANDREW, OF ANDALUSIA, AND WILSON HEMINGWAY, JR., OF PHILADELPHIA, PENNSYLVANIA, ASSIGNEES, BY DIRECT AND MESNE ASSIGNMENTS, TO THE ELECTROLOCK MANUFACTURING COMPANY, OF VICKSBURG, MISSISSIPPI, A CORPORATION OF MISSISSIPPI

IGNITION-SWITCH LOCK

Application filed September 29, 1927. Serial No. 222,713.

- Our invention relates to ignition switch locks of a character in which when the switch is moved into open or "off" position it is automatically locked in such position.
- 5 It is a general object of the invention to provide a switch of simple construction in which the contacts by means of which the ignition circuit is opened and closed are slidably related to each other.
- 10 It also is an object of the invention to provide a construction in which one of the contacts of the switch is mounted upon a reciprocatory lock structure and is adapted to be reciprocated therewith to effect the opening and closing of the said switch.
- 15 It is a further object of the invention to provide one of the contacts of the switch with means whereby upon the movement thereof into "off" position certain portions 20 of the ignition circuit are grounded.
- 20 To these and other ends the invention comprehends the construction and arrangement of parts as hereinafter described in detail, particularly pointed out in the claims and as 25 illustrated in the drawing in which we have illustrated one form of mechanical embodiment of the invention. However, it will be understood that the invention may be embodied in forms of construction other than 30 that shown and that changes in the details of construction may be made within the scope of the claims without departing from the spirit of the invention or the principle thereof.
- 35 In order that the invention may be more readily understood and its practical advantages fully appreciated, reference should be had to the accompanying drawing in which: 40 Fig. 1 is a view in longitudinal central section of an ignition switch lock structure embodying our invention;
- 45 Fig. 2 is a similar view with the co-operative parts thereof shown in different relative positions with respect to each other;
- 50 Fig. 3 is a transverse sectional view taken on the line 3—3 of Fig. 1; and
- 55 Fig. 4 is a view in sectional side elevation of a fragmentary portion of the structure showing more clearly certain details of construction.
- In the drawing we have shown a switch casing 1 removably supported within a split sleeve 2, permanently mounted within a split tubular support 4, having ears 5 secured by rivets 6 to the dash-board or plate 7 of metal 55 of an automobile, truck or the like. Instead of employing rivets for securing the ears 5 to the plate 7, they may be secured thereto by any other means, as by spot welding. The split sleeve 2 is secured to the tubular support 4 preferably by spot welding as indicated at 10. The opposite ends of the sleeve 2 are free from the tubular support 4 and are provided with projections or ears 11 which extend laterally through a slot or 60 notch 12 in the rear edge of the tubular support 4. The ears or projections 11 are provided with openings therethrough through which a bolt 13 extends, provided with a head at one end and screw threads at the other, 65 for the reception of a nut 14, which is adjustable. By tightening the nut 14 the split sleeve 2 may be clamped upon the switch casing 1 to hold the same in stationary position thereon and by loosening the said nut, the 70 said casing may be removed if desired, unless it be locked to the said sleeve in the manner hereinafter described.
- 75 Mounted within the switch casing 1 is a block of insulating material 20 of elongated 80 shape, the surface of one side of which is cylindrical as indicated at 21, which contacts with a portion of the cylindrical interior surface of the switch casing 1. The opposite side of the said block is provided with square 85 cornered grooves 22, which extend longitudinally thereof. The cylindrical surface 21 is provided with a projection 23, which when the block 20 is in place as shown in 90 the drawing, projects outwardly through an opening 24 in the switch casing 1. The block 20 is wedged and held in place by means of a wedge 25, which in cross section is substantially semi-circular in shape. The opposite 95 edges of the wedge 25 are tapered as shown and rest against the bottoms of the notches 22. After the block is placed in position with the projection 23 extending through the opening 24, the wedge being tapered as shown, 100

may readily be removed should occasion require.

A stationary contact 30 is mounted upon the front portion of the block 20 intermediate the grooves 22. A binding post 31 extends through an opening 32 extending through the projection 23 and partly through the block 20. The post 31 is provided with a reduced end portion which extends through the remaining portion of the block 20 and through the contact 30 and is upset as indicated at 33 to act as a rivet for securing the contact 30 permanently to the said block. The post 31 is provided with a screw threaded opening 36 adapted to receive a binding screw 37 to which one end of a conducting wire 38 is connected, the opposite end of which is connected to one end or side of a primary coil 39 of a transformer, the opposite end of which is connected to the positive side of a battery 40, the opposite side of which is grounded as indicated at 41.

The contact 30 is provided with a bent, raised portion 45 with which one side 46 of a U shaped contact 47 is adapted to contact. The opposite side 48 of the said U shaped contact is adapted to contact with the contact portion 49 of a spring contact 50, mounted at its inner end upon the rear end of the block 20 and being secured thereto by means of a fastening screw 51. The U shaped contact 47 extends over and incloses the upper and lower sides of the inner end of a sheet 53 of insulating material and is secured thereto by means of rivets 54. At its opposite end the sheet 53 of insulating material is secured by rivets 55 to the forwardly extending portion 56 of a bent metal connection, the opposite transverse extending portion 57 of which is secured by means of binding screws 59 to the inner end of a lock cylinder 60, mounted in the front or forward end portion of the switch casing 1. The said lock cylinder is adapted to be moved inwardly and outwardly in the said casing. The back and forth movement of the lock cylinder 60 is limited by means of a screw 60^a secured in the side thereof and projecting into a slot 60^b provided in the inner side of the casing 1, the said screw and slot being indicated by dash and dot lines in Figs. 1 and 2 of the drawing.

When the lock cylinder is moved inwardly within the casing 1 into locking position as shown in Fig. 2 of the drawing, it compresses a spring 61 located between the lock cylinder and the opposing end of the block 11 of insulating material. When the cylinder is thus moved into locking position the lock bolt 65 which is pressed outwardly by a spring (which is not shown) within the lock cylinder engages openings 66 and 67 in the switch casing 1 and split sleeve 2 respectively as shown. When the lock cylinder is in the latter position the switch is in open or

"off" position. At such time the contact portion 45 of the contact 30 is in contact with the underside of the sheet 53 of insulation, while the raised contact portion 49 of the contact 50 is in contact with the metal portion 56 which is supported upon the metal lock cylinder 60 and is thereby grounded. The lock bolt 65 is adapted to be disengaged from the openings 66 and 67 by means of a key indicated at 70 and when released the spring 61 which has been compressed by the pushing inwardly of the lock cylinder 60 expands and forces the lock cylinder out into the position indicated in Fig. 1.

The screw 51 previously referred to also operates to hold the metal member 75 in place upon the inner end of the block 20 of insulation and in contact with the front end portion of the contact 50. A conducting wire 76 is connected at its front end to the member 75 and its opposite end to a timer indicated at 77.

When the lock cylinder 60 has been pushed inwardly into locked position as shown in Fig. 2 of the drawing with the portion 45 of the contact 30 in contact with the sheet 53 and with the portion 49 of the contact 50 in contact with the metal supporting portion 56, it will be apparent that the circuit from the battery through the coil 39, the line 38, the contacts 30, 47 and 50 and the line 76, the timer and the ground are broken and it also will be apparent that the timer and conducting line or wire 76 are grounded through the contact 50, the lock cylinder and the plate 100 7 so that it becomes impractical for anyone except with a proper key to complete the circuit through the battery and the timer. It will be noted that in the operation of the switch, the contacts thereof make sliding contact with each other in consequence of which they are kept clean and the formation of deposits thereon is prevented. It follows that perfect contact is made at all times.

Having thus described our invention what we claim and desire to secure by Letters Patent is:

1. In an ignition switch lock the combination of a switch casing, a block of insulating material mounted in said casing, a wedge for retaining the said block within the said casing, said wedge being of semi-circular shape, contacts stationarily mounted upon said block, and a contact slidably movable into and out of contact with the said stationarily mounted contacts.

2. In an ignition switch lock, the combination of a switch casing, a block of insulating material mounted therein, contacts mounted on said block, which contacts are located in opposed relation to each other, a sheet of insulating material adapted to be moved back and forth between the said contacts, a contact carried by the said sheet and adapted to be interposed by the movements of said sheet 130

- between the said first named contacts, and means for grounding one of the first named contacts when the movable contact carried by the said sheet of insulating material is moved 5 out of contact with the contacts mounted upon the said block.
3. In an ignition switch lock for automobiles, the combination of a switch casing, a block of insulating material mounted there- 10 in, a contact carried by the said block, another contact carried by said block, a locking device mounted within the said switch casing and adapted to be reciprocated therein, a sheet of insulating material carried by the said 15 locking device and extending between said contacts, and a contact carried by said sheet of insulating material and adapted to be slidably moved into and out of contact with the first named contacts by the movements of the 20 said locking device out of and into locking position.
4. In an ignition switch lock, the combination of a casing having an opening in one side thereof, a block of insulating material 25 mounted in said casing having a projection thereon which extends through said opening, the opposite side portion of said block being provided with a couple of grooves located in the opposite edges thereof and in 30 adjoining relation to adjoining portions of the sides of said casing, a wedge for retaining the said block within said casing, said wedge being of semi-circular shape, the opposite edges of which are in engagement with the 35 bottoms of said grooves, and the opposite convex portion of said wedge being in contact with a portion of the said casing opposite the said block, contacts stationarily mounted upon the said block, and a contact 40 adapted to be moved slidably with respect to the said stationarily mounted contacts into and out of engagement therewith to close and open the said switch.
5. In an ignition switch lock, the combination of a casing, a block of insulating material mounted within said casing, contacts mounted upon said block, the contact portions thereof being located in opposed relation to each other, a locking device mounted 45 50 within said casing and adapted to be reciprocated therein, the said locking device having a thin metal member projecting inwardly therefrom, a sheet of insulating material mounted upon one side of said member and a U shaped contact mounted upon and in- 55 closing the inner end of the said sheet of insulating material, the outer end of the said last mentioned contact being spaced from the said member, the said U shaped contact sliding into and out of contact with the first named contacts upon movement of the said locking device outwardly and inwardly within the said casing and the said member being 60 65 in contact with one of the first named contacts when the said locking device is in its locking position.
6. In an ignition switch lock, the combination of a casing, a block of insulating material detachably mounted therein, a contact 70 stationarily mounted upon the said block, a second contact mounted upon the said block, the contact portions of said contacts being located in opposed relation with respect to each other, a locking device having locking 75 means adapted to engage the said casing upon movement of the said locking device into locking position, the said locking device having upon its inner end an inwardly projecting thin metal member, a sheet of insulating material mounted upon one side of said member, the said sheet of insulating material extending inwardly between the contact portions of the said contacts, and contacts mounted upon the opposite sides of the 80 inner end portion of the said sheet of insulating material which contacts are electrically connected and the said last mentioned contacts being located between and in contact with the first named contacts when the 85 said locking device is in its outermost unlocked position and being out of contact therewith when the said locking device is in its innermost locked position, and the said member in the latter position of said lock being in contact with the contact portion of one of the first named contacts.
7. In an ignition switch lock, the combination of a switch casing, a block of insulating material mounted within said casing, a contact mounted upon said block, a second contact mounted upon said block, the contact portions of said contacts being located in spaced parallel planes, a locking device located within the outer end portion of said 90 casing and having a metal member projecting inwardly from the inner end thereof, said locking device being movable inwardly and outwardly into locked and unlocked positions, a sheet of insulating material mounted upon said member and projecting inwardly between the contact portions of the said contacts and contacts mounted upon the opposite sides of the inner end portion of said sheet of insulating material, which contacts are electrically connected with each other, and the said last 95 named contacts being slidably movable inwardly and outwardly with respect to the contact portions of the first named contacts 100 out of and into contact therewith.
8. In an electric switch lock, the combination of a casing, a block of insulating material mounted within the inner end portion of said casing, a contact mounted upon the 105 said block, a second contact mounted upon the said block, the contact portions of said contacts being located in opposed relation to each other, a locking device mounted and adapted to reciprocate within the outer end 110 115 120 125 130

portion of the said casing, said locking device having upon its inner end an inwardly extending projection of metal, a sheet of insulating material mounted upon the said member and extending inwardly between the contact portions of the said contacts, contacts mounted upon the opposite sides of the inner end portion of the said sheet of insulating material, which contacts are electrically connected with each other and the said contacts adapted to be moved slidably into and out of contact with the contact portions of the first named contacts upon the movement of the said locking device out of and into locking position, and a resilient yielding means located between the inner end of the said locking device and the outer end of the said insulating block, which means exerts a yielding pressure against the said locking device and tends to move and to hold the same in its outermost unlocked position.

9. In an ignition switch lock for automobiles, the combination of a tubular switch casing, a tubular support for detachably supporting said casing, contacts mounted within said casing, a locking device mounted within the front end portion of said casing and adapted to be moved axially of the said opening into and out of locking position therein, and a contact carried by said locking device, which contact is adapted to be moved by the movements of said locking device into and out of contact with the first named contacts to close and open the ignition circuit, the said locking device, when moved into position to open the switch, operating to lock the same in open position and to lock the said casing to its support.

10. In an ignition switch lock for automobiles, the combination of a tubular switch casing, a tubular support for detachably supporting said casing, the said casing and the said support having openings in their sides which are in registry with each other, contacts mounted within said casing, a locking device mounted within the front end portion of said casing and adapted to be moved axially thereof into and out of locking position therein, and a contact mounted upon the inner end of the said locking device which contact is adapted to be moved by the movements of said locking device into and out of contact with the first named contacts to close and open the ignition circuit, the said locking device having means which, when the lock is moved into position to open the said switch, moves into engagement with the said openings to lock the switch in open position and to lock the said switch casing to its support.

11. In an ignition switch lock, the combination of a switch casing, a block of insulating material mounted in said casing, a wedge for retaining the said block therein, stationary contacts mounted upon the said block, and a contact adapted to be moved

into and out of contact with the said stationary contacts.

12. In an ignition switch lock, the combination of a switch casing having an elongated block of insulating material mounted therein, a support for said casing, a wedge mounted in said casing in engagement with the said block, means for retaining the said wedge within the said casing, a stationary contact mounted upon the said block, a contact adapted to be moved into and out of contact with the said stationary contact, and means for locking said movable contact out of contact with the said stationary contact and for locking the said casing to its support. 70 75 80

13. In an ignition switch lock, the combination of a switch casing, a block of insulating material mounted in said casing one side of which is provided with a couple of grooves located in the opposite edges thereof, a wedge for retaining the said block within the said casing said wedge being of semicircular shape, the opposite edges of which engage with the bottoms of the said grooves and the opposite converse portion of said wedge 90 being in contact with a portion of the casing opposite the said block, a stationary contact mounted on said block, and a contact adapted to be moved into and out of engagement therewith. 85 95

14. In an ignition switch lock, the combination of a switch casing, a block of insulating material mounted in said casing, one side of said block being provided with a couple of grooves located in the opposite edges thereof, a wedge for retaining the said block in the said casing, the said wedge being of semicircular shape the opposite edges of which engage with the bottoms of said grooves and the opposite convex portion of said wedge 100 105 being in contact with a portion of said casing opposite the said block, a stationary contact mounted on said block, a contact adapted to be moved into and out of engagement with the said stationary contact, a tubular support for the said casing, and means for locking the said casing to the support and for locking the movable contact out of engagement with the said stationary contact. 110 115

In testimony whereof the said FREDERICK W. ANDREW has hereunto signed his name this 13th day of September, 1927, and the said WILSON HEMINGWAY, Jr., has hereunto signed his name this 21st day of September, 1927. 120 115
